RAILROAD TRACK EQUIPMENT

Warren C. Heidenthal, Middletown, N. Y., assignor to American Brake Shoe Company, New York, N. Y., a corporation of Delaware

Application October 2, 1943, Serial No. 504,666

5 Claims. (Cl. 184—3)

The invention relates in general to railroad track equipment and, more particularly, to devices for lubricating the flanges of car wheels and the flange engaging surfaces of the rails.

The invention relates further to operating mechanism which, when actuated by the passage of rolling stock, operates pumping apparatus for supplying lubricant to the rails and represents an improvement over Fuller application, Serial No. 375,898, filed January 25, 1941, now Patent No. 2,349,259, dated May 23, 1944.

According to the prior invention, a flexible cable is connected to a wheel-engaging ramp secured to the running rail and to a suitable spring device associated with the lubricant reservoir. Depressing the ramp operates the cable, which in turn operates the pumping system for supplying the rail with lubricant. The ramp is pivoted to a housing plate secured to the rail and supporting a ramp spring for holding the ramp in the path of the car wheels. The housing plate is provided with a bell crank lever, one arm of which is connected to the ramp and the other arm of which is connected to the operating cable. The lubricant reservoir is seated in the ground alongside the track and contains the pumps for delivering the lubricant to the track. The reservoir contains a spring, a unidirectional clutch and drum, the cable being wrapped around the drum and secured to the reservoir spring. The cable is thus held under tension by the two springs at all times.

The present invention relates to a new type of connection between the ramp and bell crank lever; a novel form of shim adjustment for adjusting the throw of the ramp, an improved adjustable mounting for the spring assembly in the reservoir; and a new manner of supporting the protecting pipe which protects the cable.

The invention also consists in certain new and original features of construction and combination of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part hereof, in which

Fig. 1 is a plan view of a section of track to which a lubricating device according to the invention is applied;

Fig. 2 is a vertical transverse section taken on the line 2—2 of Fig. 1;

Fig. 3 is a vertical section through the lubricant reservoir;

Figs. 4 and 5 are sections taken on the lines 4—4 and 5—5 respectively of Fig. 3;

Fig. 6 is a plan view of the ramp assembly;

Fig. 7 is an elevation thereof;

Fig. 8 is a section on the line 8—8 of Fig. 6 illustrating the bell crank lever;

Fig. 9 is a section on the line 9—9 of Fig. 6 illustrating the delivery plate;

Fig. 10 is a section on the line 10—10 of Fig. 6 illustrating the housing plate;

Fig. 11 is a section on the line 11—11 of Fig. 6 illustrating the adjusting shims;

Fig. 12 is a section on the line 12—12 of Fig. 6 illustrating the ramp spring;

Fig. 13 is a section on the line 13—13 of Fig. 6 illustrating the ramp pivot;

Fig. 14 is a section on the line 14—14 of Fig. 8 illustrating the bell connection between bell crank and ramp;

Fig. 15 is a section through the overrunning clutch;

Fig. 16 is a side view of the overrunning clutch mechanism; and

Fig. 17 is a section on the line 17—17 of Fig. 7 with cover plate removed illustrating use of chisel to pry down ramp to change shim adjustment.

Like reference characters denote like parts in the several figures of the drawings.

Referring now to the drawings and more particularly to Figs. 1 and 2 for a general description of the invention, the running rail, to which the lubricator is applied, is denoted by 15, resting on the usual ties 16 with the usual tie plates 17 interposed. Secured to the inner side of the rail 15 is the delivery plate 18 for delivering lubricant to the wheel flanges. The reservoir comprises a tank 19 set into the ground alongside the track

so as to occupy a substantially fixed position unaffected by the wave movement of the rails or ties due to the passage of railway trains. The reservoir tank 19 houses a series of pumps 20 which deliver lubricant through pipes 21 to the delivery plate 18.

Secured to the running rail is a ramp assembly, including ramp 22 which operates a bell crank lever 23 (Fig. 8) to which is secured cable 24. The cable 24 extends through the wall of the tank 19 and is wrapped several times around the drum 25 of the unidirectional clutch assembly 26 and is connected to spring assembly 26. A chain 27 connects the clutch assembly and the pumps 20, it being understood that up and down movement of ramp 22 pulls cable 24 driving drum 25 and its

unidirectional clutch, in turn driving the chain 21 and the pumps 20.

Referring now also to Figs. 9 and 10, the lubricant applying apparatus will first be described. The head 30 of T-rail 15 is cut away, as indicated at 31, and the delivery plate 18 is spaced from the rail by suitable gaskets or washers indicated by 32 to form a series of lubricant chambers 33 with the web 34, extending along the track. The delivery plate 18 is clamped to the running rail 15 by a series of nut and bolt assemblies indicated by 38. The several lubricant chambers 33 are supplied by branch pipes 35 supplied by the delivery pipes 21 and grease is fed to the wheel flanges 36 through delivery slots 39.

Attention is called to Heidenthal Patent No. 2,185,810, granted January 2, 1940, for a more complete description of the lubricant applying apparatus.

Referring now also to Figs. 6 to 14, the ramp assembly will now be described. This construction comprises the inner or filler plate 41 fitting the web 34, which may extend along the rail substantially the same distance as the lubricant applying apparatus for the purpose of reinforcing the cut away rail 15. An outer, housing plate 42 has upper pads 50, 51 (Figs. 11, 10) abutting the head of rail 15 at each end of the ramp 22 and lower pads 43, 44 (Figs. 12, 10) bearing against the filler plate 41 and against the base flange of rail 15. Plates 41 and 42 are clamped to the running rail 15 by two of the nut and bolt assemblies 38 which are used to clamp the delivery plate 18 to the rail (Fig. 6). Plate 42 is provided with flanges 126, 127 abutting the heads of bolts 38 to keep them from turning.

The housing plate 42 carries a pivot shaft 45 pinned thereto by a pin 46 passing through an adjacent flange on the housing plate, as indicated particularly in Figs. 6, 7 and 13. The ramp 22 carries a bushing 54 by which it is journaled on shaft 45. Ramp 22 carries lubricant fitting 61 for bearing 54. Access to fitting 61 is achieved through a removable plate 62 on housing plate 42.

The ramp 22 has its upper surface suitably tapered in both directions, as indicated by 47 and 48, for traffic in either direction. The upper wheel-engaging surface may be suitably hardened to withstand the wear due to the engagement of the wheel treads 37. The ramp 22 has a nose 49 which is disposed under shoulder 50 secured to the housing plate 42 to limit the upper position of the ramp (Fig. 11).

An adjustable shim arrangement is associated with the nose 49 and shoulder 50 for the purpose of adjusting the stroke of the ramp 22. The housing plate 42 is provided with a set of openings in its side wall separated by a web 40 and closed by a cover plate 88. A flange 87 integral with web 40 passes through an opening in cover plate 88 and is provided with a hole 89 for the reception of a pin or a lock (not shown) for the purpose of securing cover plate 88 in the position shown in Figure 11. Removal of cover plate 88 gives access to the adjustable shim arrangement.

The adjustable shim arrangement comprises a master shim 63 seated upon a plurality of different size lower shims 71. Resting upon the master shim 63 is a U-shaped yoke 64 surrounding nose 49. Yoke 64 has upper and lower legs 124 connected by a vertical span 125. Upper leg 124 has a raised flange 123 (Fig. 7). Lower shims 71 and yoke 64 are snugly seated in a recess 121 formed in housing plate 42.

Resting upon yoke 64 are additional different size shims 70. The upper shims 70 and upper leg of yoke 64 are disposed over the nose 49 and are held snugly in a chamber formed, on the one side, by the vertical wall 122 of the ramp 22 and, on the other side, by a raised flange 123 on yoke 64.

It will be understood that the upper shims 70 define the upper limit of ramp movement and, consequently, the stroke which the ramp 22 partakes upon the passage of the wheels of trains along the running rail 15. To change this stroke it is only necessary to remove the cover plate 88 and transfer the proper size shims from the lower group 71 to the upper group 70, or vice versa. The distance between upper and lower legs 124 is ample to take care of the throw of the ramp 22.

Normally, the ramp spring 52 holds the ramp 22 in upper position with the ramp nose 49 exerting pressure upon the upper shims 70. To adjust shims it is only necessary to remove cover plate 88 and insert a chisel or screw driver between the lower edge of shoulder 50 and the anvil 116 (see Fig. 17) formed on the end of ramp nose 49. By pressing the chisel or screw driver upwardly, the ramp may be pried downwardly against the pressure of the ramp spring. This relieves pressure on upper shims 70 and permits removal of shims and replacement of shims of different size. The master shim 63 is not shown in Fig. 17, having been removed, to give more convenient access to the lower shims 71, while adjusting shims.

The housing plate 42 (Fig. 12) is provided with a recess 53, forming a seat and housing for ramp spring 52 located under ramp 22. A drain 60 at the bottom of the spring housing prevents collection of water. It will be understood that the ramp is of such shape as to clear bolts 38 and nipple 55 threaded into web 34 to which branch 35 is connected for supplying lubricant to chamber 33.

Referring now also to Fig. 8, the housing plate 42 has an enlarged integral chamber 56. Through the end walls of chamber 56 a shaft 57 is passed, the shaft being anchored in position by a wedge 57' passing through the shaft and through a hub on the housing 56, as illustrated more particularly in Fig. 6. Journaled on shaft 57 is a bell crank lever 23 having bushing 65 and having an arm 58 connected to the ramp 22 by a ball connection. The ball 59 is disposed between a curved socket 74 in arm 58 and a hardened flat surface plate 81 fixed to the bottom of a hole 90 in ramp 22 (see also Fig. 14). A small helical spring 66, centered on a boss 98 secured to arm 58, acts between the top of hole 90 and the arm 58 to hold the ball 59 in position. The bell crank 23 is provided with a lubricant fitting 114 access to which is obtained through a removable cover 115 closing a hole in the top of housing 56.

It will be understood that, as the ramp moves up and down, it must communicate its motion to arm 58 and the ball 59 must communicate this movement without any lost motion. The bell crank arm 58 and the ramp 22 describe slight arcs in planes at right angles to each other and the ball 59 together with the surfaces of 74 and 81 accommodates this difference in movement.

Bell crank lever 23 has a depending arm 67 provided with a circular cable race 68 and a recess 69. The end of cable 24 is anchored in recess 69 in any suitable way and it rides in the circular groove 68 so that the cable 24 always has true tangential relationship with the arm 67.

at constant radius as the latter moves under the influence of the ramp.

Referring now to Fig. 3, the tank 19 comprises a casing 72 having a removable cover 73. Secured to the bottom of the tank are a series of gear pumps 20, each of which comprises gears 75 and 76 (Fig. 5), whose upper sides are exposed to the grease in the tank. Upon movement of the gears 75 and 76 in the direction indicated by the arrows in Fig. 5, the grease is forced through ducts 77 into delivery pipes 78 which connect with the delivery pipes 21 through rubber hoses 28. The gears 75 of the several pumps are mounted on drive shafts 79 which are aligned and connected by couplings 80, the drive shaft of the end pump supporting a sprocket 82.

Referring now to Figs. 3, 4, 15 and 16, a clutch assembly 86 is provided above the level of the lubricant in the reservoir. This assembly includes a bracket 83 suitably bolted to the side of the tank and supporting bearings for a shaft 84, to which sprocket 85 is pinned. A chain 27 rides on sprockets 82 and 85.

The unidirectional roll clutch 86 comprises an outer ring or drum 25 having a grooved periphery around which several turns of cable 24 are wrapped. Within the ring 25 is a hexagonal core 88 fixedly secured to shaft 84 and supporting a series of rollers 89 held in position by a series of springs 90 anchored on the hexagonal surface of core 88. An integral flange 91 and a plate 92, bolted to drum 25, ride against core 88 and hold the unidirectional clutch in assembled relationship. It will be understood that, as the outer ring 25 is rotated by movement of the cable 24 in one direction, it will impart no movement to shaft 84 and sprocket 85, but when moved in the other direction, it will drive members 84 and 85, which in turn drive the pumps 20 for pumping lubricant to the lubricant distributing apparatus.

For insuring no retrograde movement of shaft 84 when the overriding clutch executes its retracting stroke, a fibre brake 110 is provided comprising shoes 111 and 112 connected by bolts 93 and 94. A spring 95 is interposed between the head of bolt 94 and the shoe 111 to yieldably hold shoes 111 and 112 in contact with shaft 84. Shoe 112 is suitably anchored to support 83 by bolt 113. The shoes 111 and 112 have fibre linings which frictionally engage shaft 84, exercising sufficient braking action to prevent retrograde movement of the shaft 84, but not enough to prevent forward movement of the shaft 84 for pumping grease. It will be understood that other types of unidirectional clutches may be used and other devices may be provided for preventing retrograde movement.

For anchoring the end of cable 24 in the reservoir 19 a spring assembly 26 is provided (Figs. 2 and 4). This assembly comprises a pair of bolts 96 secured to the wall 72 of the reservoir and disposed on opposite sides of the sleeve 97. The heads of bolts 96 engage flanges 120 welded to the walls 72 to prevent rotation of the bolts, and nuts 119 secure the bolts rigidly in position.

Disposed on each side of sleeve 97 is a lug or ear 117 through which the bolts 96 respectively pass. Nuts 118 clamp the ears 117 between them.

The sleeve 97 has an inturned cap 98 providing a seat for a helical spring 101 operating against a movable plug or plunger 99. The plunger 99 has a recess 100 in which the end of cable 24 is suitably anchored, this cable passing along the axis of spring 101 and through an opening in cap 98. The tension of spring 101 may be ad-

justed by moving the adjusting nuts 118 along bolts 96.

If desired, a suitable protector may be provided for the flexible cable 24 where it extends from the ramp 22 to the reservoir 19 to prevent persons accidentally stepping on the cable and stretching it. While any type of protective plate may be suitably supported above the cable 24, there is shown for purposes of illustration a heavy iron pipe 104. This pipe may be sufficiently large to adequately clear the cable and may be slidably mounted at the ramp end within a sleeve fitting 107 suitably bolted to bell crank chamber 56 (Fig. 8) by bolt 105. The fitting 107 surrounds the lower side of bell crank lever 23 closing the lower side of chamber 56 to protect the bell crank lever 23 from underneath. The sleeve 107 should preferably be somewhat larger than pipe 104 and the pipe is slidably and loosely disposed in the sleeve so as to permit angular movement between pipe 104 and the ramp assembly due to the movement of the running rail.

The reservoir end of protecting pipe 104 is connected to a nipple 106 suitably welded to the tank wall 72, a flexible tube 103 being clamped around the nipple 106 and pipe 104 by clamps 102 (Figs. 2 and 4). Packing 108 may be placed between the adjoining ends of nipple 106 and pipes 104. The rubber tube 103 and packing 108 permit angular movement between pipes 104 and reservoir 19 and also help prevent transmission of shock from track to reservoir.

Operation and advantages

It will be understood that the ramp spring 52 is normally in expanded condition (Fig. 12), while the tank spring 101 is normally held by the tension of cable 24 in compressed position (Fig. 4). As the wheel tread 37 engages ramp 22, spring 52 is compressed and the bell crank lever 23 moves in such way as to permit the flexible cable 24 to be taken up by the reservoir spring 101. This movement rotates the outer ring 25 of the unidirectional clutch 86. In the form shown, this movement is in such direction as to cause the clutch to retract and impart no movement to the gear pumps 20.

As the wheel tread 37 leaves the ramp, the ramp spring 52 moves the ramp upwardly, which pulls the cable 24 out of the reservoir against the force of spring 101, imparting rotation to the outer collar 25 of the unidirectional clutch in such direction as to drive the gear pumps 20.

It will be understood that, if desired, the action of unidirectional clutch 86 may be reversed so as to permit pumping action upon downward movement of the ramp with corresponding no pumping when the ramp moves upwardly, but it is preferred in most cases to provide pumping action only with upward movement of the ramp.

The cable 24 may be of any flexible material, such as steel or bronze, and is wrapped around the clutch drum 25 several times with sufficient tension to prevent slipping, both when the clutch 86 is engaged for driving the pumps and when the clutch is free-wheeling.

This arrangement provides a very efficient means for transferring force where it is desired to minimize lost motion. Substantially all the wearing parts are located between the main springs 52 and 101 so that all lost motion is immediately taken up by these springs. The wear in the unidirectional clutch 86 is not taken up by the springs, but such clutches are very efficient, especially when kept out of the bath of lubricant.

The lost motion in the chain and sprockets may be kept very small so as to be substantially negligible.

The invention, furthermore, has the advantage that the tank spring 101 will automatically take up any slight shifting horizontally in the track with respect to the reservoir and, when installing the apparatus, an adjustment of this spring assembly will take care of any slight variations in distance between the reservoir and the track.

As shown, the seat for ramp spring 52 is built entirely in housing plate 42. In this case, the pivoting of the ramp to the outer housing plate and the extension of the housing plate 42 to cover both ends of the ramp permits completing the ramp assembly in the factory and applying the device to the rail as a unit.

The ball connection between the ramp and bell crank insures positive operation without lost motion. The ball is free to move on the bearing surfaces, between which it is held, under influence of the diverse motion of the ramp and of the bell crank about axes at right angles to each other.

The shim adjustment provides a simple means for controlling the lubricant flow. If too much lubricant is being supplied by the pumps, it is only necessary to transfer shims from the lower set to the upper set to diminish the throw of the ramp. Likewise, if too little lubricant is being supplied by the pumps, shims will be transferred from the upper set to the lower set to increase the throw of the ramp. The removable cover plate holds the shims in position, and the lower or unused shims are always available in case different sizes are needed for the upper or used shims.

While certain novel features of the invention have been disclosed and are pointed out in the annexed claims, it will be understood that various omissions, substitutions and changes may be made by those skilled in the art without departing from the spirit of the invention.

What is claimed is:

1. In a track lubricator, a track structure including a running rail and a lubricant applying member, a lubricant supply, conveying apparatus for conveying lubricant from said supply to said lubricant applying member, an operating ramp on said track structure adapted to be moved by passage of cars on said running rail, a bell crank lever pivoted on said track structure and having one arm for connection to said ramp, said arm and ramp having opposed bearing surfaces, a ball between said surfaces, means holding said bearing surfaces in tight engagement with said ball, and means connecting said conveying apparatus and the other arm of said bell crank lever whereby movement of said ramp causes said conveying apparatus to deliver lubricant to said applying member.

2. In a rail lubricator, a track structure, a lubricant delivery member associated with said track structure for delivering lubricant to rolling stock wheels, an operating member secured to said track structure, a bell crank lever pivotally mounted on said track structure, said bell crank lever having a substantially horizontal arm and a substantially vertical arm, said horizontal arm having a curved recess in its lower face, said operating member having an opening, a ball between the lower surface of said operating member opening and said arm recess, a spring acting between the upper surface of said operating member opening and said horizontal arm, said

depending arm having an arcuate groove, a cable secured to said arm and disposed in said groove, and pumping apparatus operated by said cable for supplying said delivery member with lubricant.

3. In a rail lubricator, a running rail, a lubricant delivery member attached to the inner side of said running rail for delivering lubricant to rolling stock wheels, a filler bar attached to the outer side of said running rail, a housing plate secured to said filler bar and providing an elongate slot therebetween, a ramp disposed in said slot and pivoted to said housing plate, said housing plate having a recess, a spring in said recess disposed under said ramp, said housing plate having an abutment, said ramp having a toe disposed under said abutment to limit the upper position thereof, said housing plate having an enlarged chamber, a bell crank lever pivotally mounted in said chamber, said bell crank lever having a substantially horizontal arm and a substantially vertical arm, said horizontal arm having a curved recess in its lower face, said ramp having an opening, a ball between the lower surface of said ramp opening and said arm recess, a spring acting between the upper surface of said ramp opening and said horizontal arm, said depending arm having an arcuate groove, a cable secured to said arm and disposed in said groove, and pumping apparatus operated by said cable for supplying said delivery member with lubricant.

4. In a rail lubricator, a track structure including a running rail, a lubricant delivery member associated with said track structure for delivering lubricant to rolling stock, a housing secured to said running rail and providing an elongate slot, a ramp disposed in said slot and pivoted to said track structure, said housing having an abutment and a recess, said ramp having a nose disposed under said abutment, said nose having a raised anvil, adjusting shims located in said recess, a U-shaped yoke surrounding said nose and resting upon said adjusting shims, upper adjusting shims located above said yoke, said yoke having an upraised flange and said ramp having a vertical surface defining a space for said upper shims, said housing having an opening for access to said shims and to said anvil, a closure for said opening, and means operated by said ramp to supply lubricant to said delivery member.

5. In a rail lubricator, a track structure including a running rail, a lubricant delivery member associated with said track structure for delivering lubricant to rolling stock, a housing secured to said running rail and providing an elongate slot, a ramp disposed in said slot and pivoted to said track structure, said housing having an abutment and a recess, said ramp having a nose disposed under said abutment, said nose having a raised anvil, adjusting shims located in said recess, a U-shaped yoke surrounding said nose and resting upon said adjusting shims, upper adjusting shims located above said yoke, said yoke having an upraised flange and said ramp having a vertical surface defining a space for said upper shims, said housing having an opening for access to said shims and to said anvil, a closure for said opening having a hole, a horizontal web disposed across said opening having an apertured projecting lug disposed in said hole for a pin or the like to hold said closure in position, and means operated by said ramp to supply lubricant to said delivery member.
